UNITED STATES PATENT OFFICE.

JAMES WILEY SMALL, OF ROCHESTER, NEW YORK.

MACHINE FOR VENDING AND REGISTERING TICKETS.

1,022,159.

Specification of Letters Patent.

Patented Apr. 2, 1912.

Application filed April 29, 1911. Serial No. 624,031.

To all whom it may concern:

Be it known that I, JAMES WILEY SMALL, a citizen of the United States, residing at Rochester, in the county of Monroe and State of New York, have invented certain new and useful Improvements in Machines for Vending and Registering Tickets, of which the following is a specification:

The subject of the present invention is a machine, placed under the control of the ticket seller, which has a magazine appropriate to the form of the tickets, and which at each operation will deliver a single ticket and register it, so that the total number of tickets delivered by the machine will be shown at a glance.

A complete machine constructed in accordance with the present invention embodies two mechanisms, one for vending and the other for registering the tickets, but these two mechanisms are so intimately associated and involved, one with another, that the illustration of both is necessary to a full and complete disclosure of either and hence, while the drawings of the present application show a complete machine, the claims are confined to those features that are involved, the registering mechanism, those involved in the vending mechanism made the subject of a separate application filed November 10, 1911, Serial No. 659,598.

The object of the invention which forms the subject of the present application is to provide a machine which will accurately register the number of tickets and which is particularly adapted for use in connection with vending mechanisms constructed as shown and described, but which, manifestly, may be used in connection with vending mechanism of any construction that will co-operate with it.

To these ends the invention consists in the features of novelty that are hereinafter described with reference to the accompanying drawings, which are made a part of this specification and in which:

Figure 1 is a sectional elevation of a ticket vending and registering machine embodying the invention with one side of the casing removed, all of the movable parts being shown in elevation, while the ticket race is shown in vertical section on line 1--1, Fig. 3, and a fragment of the magazine being shown. Fig. 2 is an elevation of the delivery end of the machine, the operating lever being shown in section. Figs. 3 and 4 are

vertical transverse sections on the lines 3--3 and 4--4, Fig. 1, looking in the directions of the arrows, respectively. Fig. 5 is a horizontal section taken practically on the line 5--5; Fig. 6, looking downward. Fig. 6 is a detail showing the mechanism for locking the register. All of the foregoing figures are drawn on practically full scale. Fig. 7 is a side elevation on a smaller scale of a machine embodying the invention.

For the purpose of this application I have shown the invention as embodied in a machine which is adapted to vend tickets which are printed upon a continuous strip which is afterward done up in the form of a roll, but it will be manifest that some features of the invention are applicable to the vending and registering of tickets of other forms, and I therefore reserve to myself the exclusive right to use the several features of the invention in any machine in which they are capable of use.

The machine shown in the drawings has a circular magazine, 10, which contains the roll, 11, of tickets that is supported by a trunnion, 12. For facility in placing the roll of tickets within the magazine, the latter is formed in two parts (practically halves) which are hinged together, as at 13, and one of these parts is provided with a chute, 14, for guiding the free end of the ticket strip to the delivering and registering mechanism. The individual tickets may or may not be separated by weakened lines but they must be provided with such physical features that will provide shoulders adapted to be engaged by the feed dogs and oppositely presented shoulders which are adapted to engage and actuate the registering mechanism. To this end one or both edges of the ticket strip are provided with a series of notches, 15 and 15^a, which preferably occur between adjacent tickets.

From the chute, 14, the tickets pass on to the bottom, 16, of a race, which extends completely through the casing, 17, to the delivery end, 18, thereof, which latter is provided with an opening through which the tickets emerge. This race comprises the bottom, 16, and two sides, 19, which are just sufficiently far apart to allow the tickets to pass freely between them, without binding. The bottom, 16, of the race is provided in its top side with parallel grooves, 20 and 20^a, which are of sufficient distance apart to register with or lie beneath the notches, 15

and 15^a, respectively in the sides of the ticket strip. The ticket strip is held down upon the bottom of the race, especially where it is engaged by the feed dogs and the registering mechanism, by a plate spring 21, one end of which, 22, is secured to the receiving end, 23, while the other end, 24, rests upon the ticket-strip by which and an inclined guide, 25, the free end of the ticket strip is guided into the aforesaid opening through the delivery end, 18, of the casing. The tickets are fed forward by a pair of spring pressed dogs, 26 and 26^a, the toes of which are adapted to enter the notches of the ticket strip. These feed dogs are in the form of levers which are independently fulcrumed upon a pin, 27, carried by a pendent hanger formed of two parts, 28 and 28^a, the upper end of which parts are rigidly secured to flanges of an arbor, 29, loosely fulcrumed in the front and back of the casing, spacing sleeves, 30, being loosely mounted upon the arbor between the casing and the hanger for the purpose of permitting the hanger to swing freely and at the same time confine it to proper position. The dogs are held yieldingly in engaging positions by delicate coiled springs, 31 and 31^a, each of which is connected at one end to the projecting heel end of the dog and at the other end to the hanger, and in order to prevent the lower ends of the two parts of the hanger from clamping and binding the dogs, so as to prevent their absolutely free movement they are spaced apart by shoulders on the rivets, 28^b, by which they are connected. The dogs are reciprocated back and forth each time through a distance equal to the length of a single ticket, by the oscillation of the hanger, and this oscillation is produced by a bell crank lever, 32, one arm, 33, of which has a radially disposed slot, 34, into which projects a pin, 35, carried by the hanger, while the other arm, 40, of said bell crank lever is engaged by an anti-friction roller, 41, carried by one arm of the main or operating lever, 42, which is fulcrumed to the casing at 43, whence it projects outward through the slot, 44, in the delivery end, 18, of the casing and is provided at its outer end with a suitable handle, 45. The main lever, 42, is held in normal position, *i. e.*, with the handle, 45, up, by the heavy coiled spring, 46, and this spring, 46, acting through the main lever, will hold the feed dogs in forward positions, acting through the medium of the bell crank lever, 32, the pin, 35, and the hanger in opposition to the resistance of a lighter coiled spring, 47, which is connected at one end to the hanger and at the other end is anchored to the casing. The depressing of the handle will put the main spring, 46, under tension and will allow the spring, 47, to rock the bell crank lever in the direction of

the arrow placed upon it, and this in turn will oscillate the hanger in the direction of the arrow, thereby retracting the dogs to position for engaging the next succeeding notches, 15 and 15^a. For the purpose of limiting the movement of the parts under the influence of the spring, 47, and thereby stopping the advancing movement of the dogs at the proper point, a stop pin, 32^b, is secured to the casing in the path of the arm, 33, of the bell crank lever. When the pressure upon the handle is released, the main spring will contract and thereby depress the anti-friction roller, 41, and rock the bell crank lever and hangers in the directions opposite the arrows placed upon them in opposition to the resistance of the coiled spring, 47. This again advances the feed dogs and feeds the ticket strip forward a distance equal to the length of one ticket. Thus, it will be seen, the conditioning of the feed mechanism to operate is produced by depressing the handle, while the operation of actually feeding the ticket strip forward is produced automatically by the spring, 47. 90

Normally one ticket is always protruding from the delivery end of the casing, as shown in Fig. 7, and the depressing of the handle cuts off this ticket, and, as before stated, conditions the feeding mechanism to feed another ticket forward when the handle is released. For cutting off the tickets the main lever is provided with a projection, 48, providing a shoulder which engages a pin, 49, projecting from a cutting blade, 50, fulcrumed at 51 and operating in conjunction with a leger blade, 52, at the delivery end of the casing. The cutting blade, 50, is held normally elevated by a spring, 53, one arm of which engages a pin, 54, carried by the blade, while the other arm is anchored by a screw, 55, an intermediate operation of the spring being coiled around the fulcrum screw, 51, for the purpose of giving the spring the necessary elasticity. A spring washer, 56, is arranged between the head of the fulcrum screw, 51, and the blade for the purpose of holding the latter in proper cutting position relatively to the leger blade. 115

The sole function of the mechanism thus far described in detail, is to sever and deliver the tickets, one at a time, and has nothing whatever to do with the registering of the delivered tickets excepting that the registering mechanism derives its movement and actuating power from the ticket strip as the latter advances, so that if the supply of tickets becomes exhausted, or for any other reason a ticket is not fed forward by the operation of the mechanism so far described, the registering mechanism will not be operated. On the other hand, if the handle is not depressed to operate the feeding mechanism, and one or more tickets 130

- are drawn out, the fact will be registered. The registering mechanism has an adding train, 57, suitably supported within the casing but so as to be visible from the outside thereof. This adding train may be of any suitable or known construction and has a link, 58, mounted upon its shaft, 59, so that each time it is oscillated it will advance the unit wheel one point. To the outer end of 10 this link is pivotally connected the upper end of the thrust rod, 69, the lower end of which is pivoted at 61 near the outer end of a link, 62, the other end of which latter is pivoted to an arm, 63, of a bracket, 64, located within and suitably secured to the casing.
- To the outer end of the link, 62, preferably beyond the pivot, 61, is pivoted a star wheel, 65, which is located in the vertical 20 plane of the groove, 20, of the ticket race. As shown in the drawing this star wheel has three equidistant arms or teeth, 65^a, 65^b, and 65^c, and the extremity of each of the teeth is provided with a notch to insure its engagement with the shoulders of the ticket strip, which are provided by the notches, 15. This star wheel is supported solely by a link, 62, and is therefore "floating," or in other words, capable of moving bodily up 30 and down in an arc struck from the pivotal center of the link, 62. Normally the two adjacent teeth (65^a and 65^b) of the star wheel rest upon the upper surface of the ticket strip and the star wheel is constantly urged downward by a delicate coiled spring, 66, the lower end of which is anchored at 67 to the bracket, 64, and the upper end of which is connected at 68 to the thrust rod, 69.
- 40 All of the parts of both the feeding and registering mechanism are shown in their normal positions (before the commencement of the vending operation) in all of the several figures of the drawings, excepting Fig. 45 6, which shows them at an intermediate stage during the vending operation. When the handle, 45, is depressed it will retract the dogs and move them into engagement with the next succeeding notches, 15 and 15^a, 50 of the ticket strip. During the latter part of the downward movement of the handle the projection, 48, thereof will engage the pin, 49, of the cutting blade, 50, and thereby depress it, severing the protruding ticket 55 at about the time the backward movement of the dogs is completed. Upon releasing the handle the ticket strip will be fed forward in the manner described. When the notch, 15, reaches that tooth (65^a) of the 60 star wheel which is immediately in advance of it the spring, 66, will cause said tooth to enter the notch and also the groove, 20, so that as the ticket strip continues to move forward it will engage said tooth and turn the 65 star wheel. The star wheel is thus given one-third of a revolution and its tooth (65^a) resting upon the bottom of the groove, 20, will cause the star wheel to be moved upward, to the position shown by Fig. 6, and then downward. This up and down movement of the star wheel will produce a corresponding up and down movement of the thrust rod, 69, and link, 58, and thereby advance the unit wheel of the register one 70 number.
- The only reason for notching both edges of the ticket strip and for providing two dogs is to avoid unequal or lateral strains upon the ticket strip which would tend to cause it to bind in its race, but one feed dog 80 and its accessories will suffice.
- In order to cushion the main lever, 42, when moved by the spring, 46, a block or pad, 69, is arranged in its path and is secured to the rear wall of the casing by any suitable means, such as a bracket, 70, and if desired the main lever may be notched or cut away at its point of engagement with the pad.
- What I claim as new and desire to secure 90 by Letters Patent is:
1. In a machine of the class described, the combination of a magazine having means for supporting a strip of tickets, and mechanism for registering the number of tickets delivered, said registering mechanism having a bodily movable and rotatable part provided with a series of equidistant features which are adapted to successively engage features with which ticket strip is provided at intervals, and means for transmitting the bodily movement of said part to the register, proper, whereby it is operated, and whereby its rotation brings its equidistant features, aforesaid, into position to be engaged by the successive engaging features of the ticket-strip aforesaid. 95
  2. In a machine of the class described, the combination of a magazine having means for supporting a strip of tickets, spring-actuated mechanism for feeding the ticket-strip forward, and mechanism for registering the number of tickets delivered, said registering mechanism having a bodily movable part adapted to successively engage equidistant features with a series of which the ticket-strip is provided, whereby said bodily movable part is moved to actuate the registering mechanism by movement derived from the ticket-strip, and a spring for 100 impelling said movable part into engagement with the ticket-strip, whereby their positive engagement is insured. 110
  3. In a machine of the class described, the combination of a magazine having means for supporting a strip of tickets, and mechanism for registering the number of tickets delivered, said registering mechanism having a rotatable and bodily movable star wheel, and means for transmitting move- 125

ment from said star wheel to the register proper.

4. In a machine of the class described, the combination of a magazine having means for supporting a strip of tickets, and mechanism for registering the number of tickets delivered, said registering mechanism having a star wheel provided with features adapted to engage features with which the ticket strip is provided at intervals, a link

upon which the star wheel is journaled, a link for actuating the adding train of the register proper, and a thrust rod connecting said links, whereby the register proper is operated by movement derived from the ticket strip. 15
